UNITED STATES PATENT OFFICE.

HARVEY C. LEHMAN, OF HIBBING, MINNESOTA.

DEODORIZING APPARATUS.

Application filed October 11, 1921. Serial No. 507,024.

To all whom it may concern:

Be it known that I, HARVEY C. LEHMAN, a citizen of the United States, residing at Hibbing, in the county of St. Louis and 5 State of Minnesota, have invented certain new and useful Improvements in Deodorizing Apparatus, of which the following is a specification.

The present invention constitutes improvements in portable deodorizing apparatus designed particularly for use in toilets, sick rooms, hospitals, or similar places, and it has for its primary object to provide a simple article of manufacture in the form 10 of a receptacle capable of receiving and retaining some substance for burning to destroy or counteract offensive odors.

It is further an object to provide a device of this character which possesses the necessary factors of safety when used in carrying 20 out the deodorizing process.

These and such other objects as may hereinafter appear are attained by the novel construction, combination and arrangement 25 of parts to be hereinafter specifically described and claimed.

Reference will now be had to the accompanying drawing forming a part of this application, wherein:

30 Figure 1 is a side elevation of a device constructed in accordance with this invention.

Figure 2 is a vertical sectional view of the apparatus.

35 Figure 3 is a sectional view on the line 3—3 of Figure 1 and showing the match holder for the handle.

Figure 4 is a horizontal sectional view on the line 4—4 of Figure 1.

40 Figure 5 is a detail view of one of the connecting clips for connecting the receptacle to the base.

Throughout the following detailed description and on the several figures of the drawing, similar parts are referred to by like 45 reference characters.

Referring to the drawing, the apparatus of this invention comprises a receptacle 1, the lower section 2 of which is of solid wall 50 construction, while the upper section 3 is of foraminous material. Seated within the entrance of the receptacle is a removable cover member or hopper 4 so as to provide a constricted entrance or opening 4^a through 55 which the material to be burned is adapted to be inserted into the lower or solid section

of the container. At one side is provided a convenient handle 5, the lower end of which is riveted at 6 to the solid portion 2, and the upper end of which is riveted at 7. 60 The handle is arranged so as to coact at the upper portion with the side of the foraminous section 3 so as to lend its support to this section which is connected to the lower section as indicated at 8 in Figure 2. 65

The end of the handle adjacent the upper rivet 7 is bent laterally so as to provide extension 9 to which is riveted a match box holding or retaining frame 10, shown most clearly in Figure 3. This frame is of rectangular shape and of such a size as to readily receive a box of matches of a conventional type as indicated at 11 in Figure 1. In placing the match box in position upon the frame, the tray portion is shoved outwardly when the box is mounted in operative position thereby sustaining the box in a position where the matches are exposed and readily removable. The sides of the frame 10 coact with the sides of the box 75 upon which the abrasive material is placed so that the frame receives the pressure exerted in striking the matches upon the abrasive surface. The frame is conveniently secured to the handle extension 9 by means 80 of a rivet 12 or similar fastening means and thus the match box may be always convenient for the purpose of igniting the material to be burned.

The receptacle 1 is preferably spaced 90 from the supporting surface by means of a base in the form of a wire frame 13. This frame is composed of the lower circular wire or ring 14, the upper circular ring or wire of smaller diameter 15, and the connecting leg members 16. The upper ring 15 is received in a series of clips 17, one of which is most clearly shown in Figure 5, these clips consisting of a piece of strap material folded to form a loop 17' through 100 which the ring 15 passes, the clips being secured to the bottom of the receptacle 1 by fastening means or rivets passing through the openings 17''.

It will thus be seen that the heat from 105 material burned within the receptacle is prevented from affecting the surface upon which the apparatus is disposed.

Having in view the constricted form of the cover member 4, in the use of the device, it becomes necessary, and preferably so, to crunch up the material to be burned

into a comparatively compact wad or ball in order to pass through the mouth 4^a into the lower section of the receptacle. For the purposes of this invention, paper or similar substance may be thus balled and lighted before throwing it into the receptacle in the manner specified. In this form the paper will smoulder and burn slowly so as to give forth its particular odor through an extended period of time. The upper foraminous section 3 of the receptacle permits access of the air to the paper, the ash of which is retained in the lower solid section 2 and the fumes from the burning substance will readily escape through the foraminous section when thus constructed. The cover member 4 may readily be displaced from time to time when it becomes necessary to remove the ashes which accumulate in use.

It will be obvious that the simple construction of apparatus above described may be placed at convenient points where it is desired to provide a deodorizing or elimination of offensive odors, as hereinbefore premised, and said apparatus is particularly useful in places such as mentioned at the outstart of this description. In most instances the fumes which are given off by burning paper are entirely sufficient, though it is to be understood that the material or substance which is to be burned may have special characteristics so as to give off the proper fumes for special deodorizing operations.

Having thus described my invention, what I claim as new and desire to secure by Letters Patent is:

1. In deodorizing apparatus of the class described, a receptacle body having its lower portion formed of solid material and its

upper portion of foraminous material, and a removable hopper-like cover member formed to project inwardly of the receptacle a substantial distance and providing a constricted mouth for the receptacle. 45

2. In deodorizing apparatus of the class described, a receptacle adapted to receive and retain material to be burned and having a foraminous section through which the material to be burned is adapted to receive air, and a removable hopper shaped cover member arranged to project inwardly of the foraminous section and forming a constricted opening into the receptacle. 50 55

3. In deodorizing apparatus of the class described, a receptacle adapted to receive and retain material to be burned and composed of a lower solid wall section and an upper foraminous section connected thereto, a cover member of hopper shape loosely seated upon the top of the receptacle and having its entrance depending substantially into the same, a base composed of a wire frame, and clip means secured to the receptacle and connecting the frame to the latter. 60 65

4. In a deodorizing apparatus of the class described, a receptacle adapted to receive and retain the material to be burned, the lower portion of said receptacle having solid walls and the upper section of said receptacle being formed of foraminous material, a handle member connected to the lower solid wall section and extending upwardly in supporting engagement with the upper foraminous section, said handle being provided with match box holding means, and a cover member having an opening therein through which to insert the material to be burned into the lower section. 70 75 80

In testimony whereof I affix my signature.
HARVEY C. LEHMAN.
